UNITED STATES PATENT OFFICE.

CARL E. PEARSON, OF CLEVELAND HEIGHTS, FRANK J. KAEHNI, OF CLEVELAND, OHIO, AND GEORGE W. SMITH, JR., OF CAMDEN, NEW JERSEY, ASSIGNEES TO THE CLEVELAND TRUST COMPANY, TRUSTEE, OF CLEVELAND, OHIO, A CORPORATION OF OHIO.

SOUND-REPRODUCING DEVICE.

Application filed December 8, 1924. Serial No. 754,495.

This invention relates to means for vibrating the stylus of a phonograph reproducer, such for example as shown, described and claimed in the application of Frank 8 Kachni and William Kachni, filed May 16, 1922, Serial No. 561,415. That device consists of a magnetically vibrated member on which the usual needle rests preferably in a groove in such member. It has been found 16 that one of the types of phonographs manufactured in very large quantities has a diaphragm slightly distorted from its normal plane. The records are made accordingly and in the vibration by the needle of the 24 magnetic device referred to, the push and pull of the needle transversely of the normal plane of the diaphragm is equal in both directions. It has also been found that if the needle be firmly rested in a groove and 32 pressure be applied to the sound box of the phonograph, that increased volume of tone as well as improved quality can be obtained. The present invention, therefore, has for its 40 objects the provision of a simple, effective, 48 easily adjustable means for applying a slight pressure to counteract the distortion of any such a sounding diaphragm. Other objects include the application of such a device to a casing of a magnetically operated means 56 for actuating the needle in such an embodiment as will be capable of being cheaply manufactured and be neat and attractive in appearance.

The drawing illustrates a preferred embodiment of our invention to which the following description relates. The essential characteristics are summarized in the claims.

Fig. 1 is a side elevation of a magnetic device equipped with our invention and showing a sound box of a phonograph reproducer; Fig. 2 is a plan of the same; Fig. 3 is another elevation looking edgewise at the reproducer box and showing the diaphragm adjusting means.

In the drawing, 1 indicates the base of a magnetic device, such as referred to and provided with a suitable cover 2; 5 designates the vibrating element or reed provided with a transverse groove at the top adapted to receive the point of the needle or stylus of a phonograph, the device being adapted to stand upon the record table or at the side

thereof within the normal swinging arc of the phonograph tone arm. The actuation of the reed is caused by a variable current 55 led through a suitable wire cord shown at 3. 10 indicates the frame of the sound box of a phonograph; 12 the diaphragm thereof. The actuating lever designated 15, is pivoted to the frame of the sound box and at 18 is shown the usual needle receiving socket and securing screw.

At the side of the cover and rigidly secured thereon, preferably by rivets, a bracket arm 20 shown as carrying an upwardly projecting pin 22, adapted to engage the side of the sound box as shown, allowing vertical movement and easy positioning thereof. Pivoted on this bracket is a lever 25 having an upwardly turned portion 26 70 with an inward lip or projection 27, adapted to engage the frame of the sound box under the pressure of a thumb screw 30, shown as threaded through a suitable nut carried on an upwardly projecting ear 31 of the 75 bracket.

The parts, as shown, are so constructed as to be made from sheet metal whereby they are neat in appearance and capable of being manufactured by stamping operations.

To use the device, the phonograph sound box is moved into a position where the needle may be rested in and firmly engaged by the groove on the top of the vibration reed. The back of the sound box sliding 85 along the projecting pin 22 and the lever 25 is then urged inwardly by the screw 30 to engage the frame of the sound box. This swings the frame about the pin 22 as a pivot point and at the same time presses through 90 the needle and lever 15 to tension the diaphragm under the influence of the screw.

It will be noted that the position of the guiding pin 22 is such that the lateral vibration of the reed 5 naturally so aligns the 95 sound box and magnetic device that the vibration of the reed is exactly normal to the position of the pin, that is accurately transversely of the sound box and its diaphragm, and also that the sound box which is usually 100 pivoted may be readily lifted from the magnetic device and disengaged from the diaphragm tensioning means described. The height of the pin 22 is such that it may

gage the flat back of different sizes of the usual sound boxes.

When the pressure described is applied through the screw and lever 25, it is preferably at a point on a line between the pin 22 and the point of engagement of the needle or stylus with the vibrating reed. This reacts through the lever 15 to pull outwardly, that is, toward the adjusting screw in Fig. 2 drawing correspondingly on the diaphragm, and without tipping the sound box.

It is to be understood that various modifications of our device may be employed to tension or alter the normal plane of the diaphragm of various kinds of sound producing mechanisms. By adjusting this screw while operating with suitable current such as the output of a radio receiving apparatus, one may judge when the best results are obtained.

We claim:—

1. In a sound producing device the combination of a usual phonograph reproducer having an actuating lever and a needle, a magnetic device having a vibrating member responsive to variable current, and adapted to receive the needle and support the weight of the reproducer, a vertical shoulder supported by the magnetic device and an adjustable member pivotally mounted on the magnetic device and adapted to engage the reproducer at a point between said vertical shoulder and said actuating lever.

2. The combination with the sound producing device of phonograph, of an actuating lever pivotally mounted on the periphery thereof, a needle engaging said actuating lever to a magnetic device having a vibrating member adapted to engage said needle, means in fixed relation to said magnetic device adapted to slidably engage the sound producing mechanism and adjustable means also engaging the sound producing mechanism reacting through said magnetic device so that the relative position of the actuating lever and the sound producing mechanism may be varied by said adjustable means.

3. In a sound producing mechanism actuated by a variable current and the combination with a phonograph sound box having the usual lever and needle, of a magnetic device having a vibrating member adapted to be removably connected to the needle, means engaging the sound box allowing vertical movement thereof for disconnection of the needle and adjustable means engaging the sound box opposite the first engaging means and between the point of engagement of the needle and the vibrating member and the point of engagement of the first mentioned means and adapted to exert pressure against the sound box causing a corresponding pressure on the diaphragm.

4. In a sound producing mechanism, the

combination of a magnetic device having a vibrating member, a depression in the top of a vibrating member, a phonograph reproducer having its needle removably resting in said depression, a member established by the magnetic device having a vertical shoulder engaging one side of the sound box and an adjustable member engaging the other side of the sound box intermediately of the shoulder and point of engagement of the needle.

5. In a sound producing device the combination with the usual phonograph reproducer having an actuating lever and stylus for a disc record, a magnetic device having a vibrating member responsive to variable current and adapted to rest on the phonograph whereby the vibrating member may receive the needle and support the weight of the sound box, a laterally projecting bracket on said magnetic device having a vertical shoulder adapted to slidably engage one side of the sound box and position it with relation to the magnetic device such that it may align the parts to cause the movement of the vibrating member to be normally transverse to the plane of the diaphragm, adjustable means for exerting pressure against the opposite side of the sound box intermediately the point of the needle and the said shoulder.

6. The combination of a sound producing mechanism of a phonograph with a magnetic vibrating member for actuating the stylus of the phonograph and means cooperating with the mechanism and the member for altering the tension on the diaphragm of the phonograph.

7. A sound producing device, including the combination of a phonograph and magnetic means for operating the usual vibrating lever of a phonograph sound box, and means reacting through said magnetic means for varying the tension on the diaphragm of the sound box.

8. A sound producing device, including the combination of a phonograph and magnetic means for operating the usual vibrating lever of a phonograph sound box, and means for varying the tension on the diaphragm of the sound box, and adjustable means connected to said magnetic means for distorting the diaphragm of the sound box from its normal plane or bringing it to its true plane.

9. A sound reproducing device consisting of a combination of a phonograph reproducer, a magnetic device having a vibrating member actuating the stylus of the phonograph, and means associated with the magnetic device for putting a tension upon said needle whereby the diaphragm of the sound box may be moved toward or away from its normal plane.

10. In combination with a phonograph re-

producer having a diaphragm normally slightly distorted from a true plane, magnetic means having a vibrating member adapted to be connected with the stylus of the phonograph reproducer, and means associated with said magnetic means for bringing pressure to bear against the phonograph reproducing box when so positioned to counteract or eliminate the normal distortion of the diaphragm.

11. A sound producing device including the combination of a phonograph reprodu-

er having a vertical diaphragm and sound box and the usual stylus carrier, of a magnetic device having a vibrating member 15 adapted to be connected with said carrier and having a vertical shoulder engaging one side of the sound box, and means for bringing pressure to bear against the sound box between said shoulder and the connection 20 with the stylus carrier.
